UNITED STATES PATENT OFFICE.

WILLIAM M. WALLACE, OF BRIDGEPORT, OHIO.

GLASS-PRESS.

SPECIFICATION forming part of Letters Patent No. 281,740, dated July 24, 1883.

Application filed May 26, 1883. (No model.)

To all whom it may concern:

Be it known that I, WILLIAM M. WALLACE, of Bridgeport, in the county of Belmont and State of Ohio, have invented a new and useful Improvement in Glass-Presses; and I do hereby declare the following to be a full, clear, and exact description thereof, reference being had to the accompanying drawings, forming a part of this specification, in which—

10 Figure 1 is a front elevation of my improved machine-press. Fig. 2 is a side elevation. Fig. 3 is a vertical section on the line $x-x$ of Fig. 2, looking toward the left.

Like letters of reference indicate like parts in each.

15 Upon a suitable bed-plate, a , is bolted a standard, b , the upper end of which is bent over to form a horizontal bearing, which is recessed, as at b' , so as to form two arms, which 20 sustain two cross-heads, b^2 . The cross-heads b^2 are bored vertically, and threaded for the passage of a vertical screw-shaft, c , which is grooved or key-seated at one side, as at c' , Fig. 3.

25 Placed on the screw-shaft, between the two cross-heads b^2 , is a beveled pinion, d , having a feather, d' , which enters the key-seat c' of the shaft, so that when the pinion is rotated it causes the shaft to turn and to screw up or 30 down in the cross-heads b^2 , according as the movement of the pinion is to the right or left.

Bolted to the upper end of the standard d by means of a foot, e , is a vertical plate or bearing, e , in the upper end of which a horizontal shaft, f , is journaled. Mounted upon the shaft f is a large beveled-gear wheel, g , which meshes into the beveled pinion d , and is provided with a handle, g' , whereby it is operated. Secured to the upper end or plain 40 portion of the shaft c by means of collars h' , fastened by set-screws h^2 , is a cross-head, h . The cross-heads h and b^2 are bored at their outer ends for receiving two threaded rods, i . On the threaded portions of these rods are nuts i' , two of which are placed above the cross-head h , and two between the cross-head h and the upper cross-head, c^2 . The purpose 45 of these nuts is to limit the vertical movement of the rods. Placed on the rods, between the lower nuts, i' , and the cross-head h , are springs i^2 , and secured to the lower end of the rods is a ring, k , to which is secured a mold-ring, k' .

On the lower end of the shaft c is a head or disk, c^2 , the end of the rod being turned off 55 to form a narrower portion or neck, c^3 . Loosely secured in the neck-recess by means of the disk c^2 is a collar, l . The plunger m is fastened to the shaft c by means of a set-screw, m' , which screws against the loose collar l , so that 60 the plunger may be capable of remaining stationary while the shaft c is turning, and of being turned while the shaft c is stationary.

On the outer surface or periphery of the plunger are screw-threads m^2 , of any form or 65 shape that it may be desirable to give to the inner side of the flange of the glass cap which is made by the machine, and on the upper surface of the plunger is a ratchet, m^3 . A pawl, n , which is pivoted to the side of the shaft, 70 plays in the ratchet. A mold, o , of suitable form, is secured on the bed-plate a , being centered in any desired manner with the plunger.

The operation of my improved machine is as follows: The plunger being in the position 75 shown in Figs. 1 and 2, the requisite quantity of glass is placed in the mold. Then the wheel g is turned, by means of the handle g' , in the proper direction to cause the shaft c to screw downward in the cross-heads b^2 . The springs 80 i^2 , being in the position shown in Figs. 1 and 2, are compressed by the descent of the cross-heads h and act against the lower nuts, i' , so as to force the ring k down into the mold, in the position shown in Fig. 3, before the plunger m begins to act upon the glass in the mold. The plunger m , being loosely attached to and 85 not affected by the rotation of the shaft c , descends into the mold without rotating, and consequently presses the glass in the usual 90 manner of non-rotatory plungers. The plastic glass is pressed into the threaded recesses on the periphery of the plunger, so that a counterpart of the latter is produced on the inner surface of the flange of the cap formed in the 95 mold. When the pressing has been accomplished, the movement of the wheel g is reversed, which causes the screw-shaft c to be turned in a reverse direction and to rise in its screw-bearings b^2 , and thereby withdraw the 100 plunger from the mold. When the shaft c is thus turned in a reverse direction, the pawl n , catching on the teeth of the ratchet m^3 , causes the plunger m to be rotated with the shaft. This rotation screws the plunger out of the 105 glass cap in the mold and preserves the char-

acter and integrity of the threads formed there-
in. When the plunger has been withdrawn,
the mold is removed and the cap discharged
therefrom in the usual way. It will be noticed
5 from this description that the pressing is ac-
complished by a non-rotary plunger, and that
the withdrawal of the plunger causes its rota-
tion, so as to unscrew it from the glass.

One advantage of this method of operation
10 over that class of machines in which glass
screw-caps, telegraph-insulators, and similar
articles having screw-threads are made by first
screwing the plunger into the glass during its
descent, and then unscrewing it during its re-
15 traction, is that it does not break down or
crush the edge of the flange, which is almost
invariably the case with such machines. The
reason for this objection to these machines is,
that the power of the screw in descending is
20 so great that the movement of the plunger
must be limited with great care, and that the
workman does not usually so limit it. This
effect is further aided by the action of the in-
clined threads of the rotating plunger forcing
25 the glass down into the bottom of the mold
and packing it under the plunger, so that in
the workman's effort to get the plunger down
to the usual distance he crushes the cap by
reason of the unusual force he exerts upon the
30 machine. In my machine the plunger, de-
scending, as it does, in the usual way, is stopped
by the resistance of the glass when it has filled
the mold-cavity up to the mold-ring *k*', the
formation of the article being accomplished
35 by the dead thrust of the plunger. In addition
to this advantage, my machine imparts
an unusually smooth and perfect thread to the
glass, and is simple in construction and oper-
ation.

40 While I have shown a plunger for making
continuous threads upon glass articles, I do
not limit myself thereto, but also claim the
formation of inclined lugs or parts of screws,
and also the use of a plain-faced plunger capa-
45 ble of a dead thrust and of a rotary reverse
motion in order to give a waved or spiral-
drawn appearance to the internal surface of
glass articles.

I do not limit myself to the formation of
50 glass screw-caps, but claim also the use of the
machine for making telegraph-insulators and
all other articles to which it is applicable.
Nor do I limit myself to the devices shown
55 and described for giving a rotary movement
to the plunger during its retraction, but claim,
broadly, a plunger capable of a dead thrust
and an automatic rotary retractive motion, as
well as the particular construction shown and
described.

60 It will be noticed that the gear-wheel *g* is
large, so that the pressing motion is commu-
nicated to the plunger by a short radial stroke
or sweep of the lever *g*'. This is different
from all prior machines known to me, in that
65 such prior machines have a small gear-wheel,
and require a complete rotation to be given to

it by means of the crank. The objection to
this construction is, that the motion of the crank
must be rapid in order to secure the proper
movement of the plunger, and such rapidity 70
of motion often causes the operator to force
the plunger too far or too strongly down into
the mold, and tends to destroy or injure the
article. To obviate this difficulty stops have
been provided to limit the motion of the plun- 75
ger; but such devices are not practically use-
ful, for the reason that the quantity of glass
put into the mold often varies. By the use
of the large gear-wheel I am enabled to secure
a rapid and very powerful movement of the 80
plunger with a short and comparatively slow
stroke of the lever *g*', so that the operator is
enabled to stop the motion of the gear-wheel
with great accuracy when he feels by the re-
sistance to the plunger that the mold is full 85
and the article formed.

What I claim as my invention, and desire
to secure by Letters Patent, is—

1. In a glass-press, a plunger capable of a
dead thrust and an automatic rotary retract- 90
ive motion, substantially as and for the pur-
poses described.

2. The combination, in a glass-press, of a
plunger loosely secured to its shaft, with de- 95
vices for causing its automatic rotation dur-
ing its retraction from the mold, substan-
tially as and for the purposes described.

3. In a glass-press, the combination of a
screw-shaft, a plunger loosely attached to such
shaft, and devices whereby the plunger is 100
caused to turn with the shaft during its re-
verse movement, substantially as and for the
purposes described.

4. The combination, in a glass-press, of a
screw-shaft having a plunger loosely attached 105
thereto, and provided with a ratchet, and a
pawl attached to the shaft, so as to engage with
the ratchet during the backward or reverse
motion of the screw-shaft, substantially as and
for the purposes described. 110

5. The combination, in a glass-press, of a
screw-shaft provided with a loose plunger, and
devices for communicating the rotary motion 115
of the shaft to the plunger during its reverse
movement, with screw-bearings for the shaft,
a sliding pinion mounted on the shaft, and a
gear-wheel for operating the pinion, substan-
tially as and for the purposes described.

6. The combination, in a glass-press, of a
screw-shaft provided with a plunger, screw- 120
bearings for the shaft, a sliding pinion mounted
on the shaft, and a large gear-wheel provided
with an operating-lever for actuating the pi-
onion, substantially as and for the purposes de-
scribed. 125

In testimony whereof I have hereunto set
my hand this 21st day of May, A. D. 1883.

WILLIAM M. WALLACE.
